UNITED STATES PATENT OFFICE.

JOSEPH S. DONOVAN, OF NEW YORK, N. Y.

GAME.

SPECIFICATION forming part of Letters Patent No. 701,171, dated May 27, 1902.

Application filed March 13, 1901. Serial No. 50,995. (No model.)

To all whom it may concern:

Be it known that I, JOSEPH S. DONOVAN, a citizen of the United States, residing at New York, in the county of New York and State of New York, have invented new and useful Improvements in Games, of which the following is a specification.

This invention relates to games and game-boards of that class designed to be participated in by two or more persons and in which is employed a board or table or the like divided into a plurality of squares or sections over or upon which are designed to be moved blocks representing men or characters, the game in the present instance being designed to be instructive in its nature, being what I call a "tactical" game, the subject being that now taught at West Point and other prominent academies and will serve as a good recreation for the young student as well as the old soldier and will form a profitable manner of spending a portion of the time when not otherwise employed.

The game is a new substitute for checkers, dominoes, and chess, the first letter of each forming the name which I have chosen to give the game, which is "Cedece."

The game is to be played upon the ruled board or table, which I call the "field." The blocks or rectangular pieces are termed "officers" and "privates." The squares or movable pieces are each provided with a designating-mark designed to show the direction in which it is going. A key is provided which shows where the marked point of each piece must be.

The "field" has six diamonds or squares upon a side and so arranged that I am enabled to use colors. With the board held in one direction the first diamonds or squares are of one color; but by giving the board or table a quarter-turn the first diamonds or squares are of a different color. In this instance they are shown as black and white; but it is evident that other contrasting colors may be employed.

In the accompanying drawings, which show the preferred form of my invention, Figure 1 is a plan view of a game-board constructed in accordance with the invention, the squares upon opposite sides of the board outside the boundary-lines thereof representing the positions of the "officers" and "privates" at the

beginning of the game. Fig. 2 is a perspective view of one of the men, the "captain." Fig. 3 illustrates the key.

Like numerals of reference indicate like parts throughout the several views.

Referring now to the drawings, I will describe the invention in its preferred form. 1 designates a board or table of any suitable kind, preferably rectangular in form and having thereon a series of division-lines 2, which are disposed angularly with reference to the sides of the board or table, (seen in Fig. 1,) and as is also clearly illustrated in said figure the points or angles 5 of the rectangular blocks or pieces thus formed point toward and touch the outer boundary-lines of the board or table. As is clearly seen in Fig. 1, there are six diamonds or squares at the outer edge upon each side of the board or table. These are so disposed that while the outer diamonds or squares upon one side are of one color—say white—those upon the adjoining side at the outer edge are of a contrasting color, in this instance black.

3 represents the pieces or "men" in the form of squares of any suitable material and of a size corresponding to the size of the squares on the board or table. Each of the blocks or pieces is provided with some designating-mark 4 at one corner thereof, which is for the purpose of indicating the direction of movement of said piece. Three of each set of these pieces are further distinguished from the others and from each other to designate the "captain," "first lieutenant," and "second lieutenant." That seen in Fig. 2 represents the "captain." The square shown at the rear of the "captain" in the assemblage of squares beneath the board in Fig. 1 designates the "first lieutenant" and that to rear of the "first lieutenant" in said group represents the "second lieutenant." It will thus be seen that each piece has its designating-mark 4 to indicate the direction of movement of the square or piece, while in each group or set there are the three pieces above mentioned, having the further characteristic features or designating-marks, that of the "captain" having two parallel lines 5 upon each side of the center and these parallel marks subdivided by the double cross-lines 6, while for the "first lieutenant" the parallel lines 5 are divided by the single cross-lines 7, while the

piece representing the "second lieutenant" has the parallel lines 5 only. Furthermore, the "officers" are distinguished from the "privates" by means of two rows of dots 8, 5 while the "privates" have but one row 9 of said dots.

10 designates the key. It is provided with letters A B C, &c., and numbers, as indicated, to designate the position of the "officers" and 10 "men."

The game is played as follows: Each player should have three "officers," and twelve "privates." A command is an "officer" with one or more "privates." One player begins the 15 game by placing a command in the "field." All commands upon entering the "field" must use the first diamonds that have one point on the edge of the "field." Each player can have three independent commands in the 20 "field"—for instance, an "officer" with four "privates" in each—but cannot enter more than one command at a time. Whenever a command of more than one line enters the "field" the rear line must occupy the first 25 diamonds, and the balance must be placed in the diamonds directly in front of the rear line, like soldiers on a march. After entering the "field" a command must make all its new moves from its position in the "field." The 30 marked point of each piece must always show the direction in which it is going. To take a prisoner, one must move a piece into a space occupied by an enemy. "Officers" take and treat prisoners just the same as 35 "privates" do. Every prisoner must always be under his captor and move with him on top. To rescue a prisoner, one must make him his prisoner and treat him like one until he leaves the "field." Any number of 40 pieces can occupy one space; but the last captor must always be on top. "Officers" and "privates" must always be in communication—that is, in spaces adjoining each other. Whenever communication is broken by the 45 enemy, only those in communication with an "officer" can move. The balance cannot move until taken prisoners. An "officer" cannot move without a "private" and a "private" cannot move without an "officer." Whenever 50 the half-diamonds on the edge of the "field" cannot protect the enemy, it is possible to take prisoners by simply putting a new command in the "field" at one's turn to move. This is called an "ambush." It can be made 55 at the right, left, or your side of the "field." At your turn to move after entering the "field" select one of the fourteen moves and move one command. The letters and numbers in the key show where the marked points 60 of each piece must be on a line or at the intersection of lines, according to the move selected. The key to the moves illustrates a command of two "privates" in one line executing the fourteen different moves. If there 65 were more "privates" in a line and more lines, the whole command would move all together, like soldiers marching. The com-

manding "officer" in the key can be placed at L, G, B, H, C, K, or P upon entering the "field," after which he moves with his command. After each new move an "officer" can change his position to the front, right, left, or rear of his command, but must always be in communication.

A piece can move sidewise as far as desired, 75 but one cannot take any prisoner or prisoners with a side step, nor can one enter the "field" with a side step. The only way that one can leave the "field" is with a side step, which is made to get out of the "field" quickly, with 80 or without prisoners, or to reach the enemy's side with prisoners to make an exchange. In exchanging prisoners exchange "private" for "private," "officer" for "officer," "officer" for two "privates," two "privates" for 85 one "officer." Whenever a command exchanges prisoners, it must immediately leave the "field" with exchanged prisoners. This is called a "truce." After a "truce" a command can reenter the "field" to continue the 90 game. The victor must capture all the enemy or cripple him, so that he cannot continue the game.

The game is instructive, develops skill, and it is impossible to foretell who will be the 95 winner.

Directions or rules and explanation of the key will accompany the game, as is usual in such devices.

What I claim as new is—

1. A set of men for a game, comprising pieces each having a direction-mark at a corner, a piece having a direction-mark at a corner, and parallel lines at each side of the direction-mark, a piece having a direction-mark at a corner, parallel lines at each side of the direction-mark, and a line crossing the parallel lines at each end thereof, and a piece having a direction-mark at a corner, parallel lines at each side of the direction-mark, and parallel lines crossing the parallel lines at each end thereof.

2. A set of men for a game comprising pieces each having a direction-mark at a corner and a row of dots in line therewith, a piece having a direction-mark at a corner, parallel lines on each side of the direction-mark, and rows of dots in line with the latter, a piece having a direction-mark at a corner, parallel lines on each side of the direction-mark, a line crossing the parallel lines at each end thereof, and rows of dots in line with the direction-mark, and a piece having a direction-mark at a corner, parallel lines on each side of the direction-mark, parallel lines crossing the parallel lines at each end thereof and rows of dots in line with the direction-mark.

In testimony whereof I affix my signature in presence of two witnesses.
